UNITED STATES PATENT OFFICE

2,612,317

GUIDE FOR INDICATING THE FECUNDITY
RHYTHM IN WOMENGhislain Van Houtte and Arthur Demeuse,
Brussels, BelgiumApplication August 22, 1950, Serial No. 180,794
In Belgium August 29, 1949

2 Claims. (Cl. 235—89)

1

It cannot be denied any longer that it is of utmost importance for gynecologists as well as for women to determine rapidly and accurately, if the length of a menstrual cycle and the date of appearance of the recent menstruation are known, the date of appearance of the next menstruation to be expected, and the fecundity period of the current cycle.

The first two determinations are made by calculating the days on any calendar, and the latter determination, c. q. the fecundity period, can be easily determined by the method according to Ogino; but, apart from the fact that it meets some inconvenience to count the days on a calendar, which is necessarily not always at hand, it ensues, according to Ogino's method, that a calculation must be carried out by counting backwards from the date of appearance of the next menstruation to be expected; said operations are rather complicated and susceptible of great risks of errors.

Also, since many years, several calendars, appliances and devices have been devised for easier determining said dates; but up to the present none of the known devices have given satisfactory results and its handling is often rather complicated and requires careful attention whilst making and reading the annotations, calculating, etc., thence the risks of errors.

The present invention relates to an apparatus by means of which the date of appearance of the next menstruation and the fecundity period of the cycle under review can be rapidly determined, without calculation and, therefore, without risk of errors.

In principle, it suffices to bring the number of the day of the month of the appearance of the recent menstruation opposite of a figure corresponding to the length of the cycle under review; opposite of the current month the date of appearance of the next menstruation, and the dates of the beginning and the end of the fecundity period of the cycle under review is read.

The invention will now be further explained with reference to a few preferred embodiments, in a diagrammatic form, in perspective, as illustrated in the accompanying drawings, in which:

Fig. 1 shows one side of the apparatus being the object of the present invention.

Fig. 2 shows the other side of the same apparatus.

Fig. 3 shows another embodiment of the same apparatus, which has a slide on one side only.

In the rule 1, provided with the two lateral

guides 2 and 2', a slide 3 can be moved, having at its extremities a notch 4, 4', destined for facilitating holding and moving the slide 3 in the guides 2.

5 The top side of the guide 2 bears the figures 1 to 31, indicating the possible 31 days of a month.

Opposite of these figures 1 to 31, on the slide 3 are provided, on the same scale, the figures 33 to 23 corresponding to the various lengths of the normal menstrual cycles.

It is, of course, possible to provide, without deviating from the gist of the invention, an apparatus by means of which it is possible to 10 read the different dates when cycles longer than 33 or shorter than 23 are involved. In this case, of course, the slide 3 will bear the marks referring to the length of the cycles extending on a scale beyond the figures 33 and 23.

The slide 3 is provided with three windows referred to by figures 5, 6 and 7, arranged in staggered relation. Each of the three windows 5, 6 and 7 is cut out in the slide 3 so as to see through it the bottom of the rule 1.

25 Each of the windows 5, 6 and 7 is relative to one month or to a series of months; the window 5 is relative to the months of March, May, August, October, each having 31 days followed by a month having 30 days; the window 6 is relative to the months of April, June, September, November, each having 30 days followed by a month of 31 days; the window 7 is relative to the months of July and December, each having 31 days followed by a month of 31 days.

30 On the bottom of the rule 1, groups of three figures are inscribed one under another, indicated by 8, said groups are juxtaposed in three horizontal and parallel series 5', 6' and 7', corresponding to the three windows 5, 6 and 7.

35 The surface covered by a group 8 corresponds to the surface of a window 5, 6 or 7. By pushing the slide 3 in the guides 2 of the rule 1, the windows 5, 6 and 7 uncover each the groups of three figures 8. These three figures are in the order from high to low; the number of the day of the month in the beginning of the fecundity period, the number of the day of the month at the end of the fecundity period and the number of the day of the month indicating the date of appearance of the next menstruation to be expected.

40 These figures, representing the numbers of the days of the month, are relative to the month under review; if they refer to the next month, they are provided with a background of different color; if necessary, if they refer to

a second month after the month under review, they are provided with a background of still another color.

The determination of the fecundity period of a woman and of the date of appearance of the next menstruation to be expected, if the date of appearance of the recent menstruation and the length of the menstrual cycle are known, is very easily effected by pushing the slide 3 until the figures referring to the length of the cycle of the person to be examined, are superposed (figures provided on the slide 3 and figures generally indicated by 9), and the reference marks referring to the number of the day of the month (provided on the guide 2 and figures generally indicated by 10) corresponding to the date of appearance of the recent menstruation. Through the window corresponding to the month of appearance of the recent menstruation, three superposed figures are visible, if desired, provided on the bottom in different colors; the first figure refers to the date of the beginning, the second to the date of the end of the fecundity period, at last the third figure refers to the date of appearance of the next menstruation to be expected.

Example 1.—The recent menstruation of a woman having a menstrual cycle of 28 days, started on March 17th. By pushing the slide 3 in the guides 2, so that the reference mark 28 (length of the cycle) comes opposite of the figure 17 on the guide 2 (number of the day of the month), the three figures: 26 on a white background; 2 on a yellow background and 14 on a yellow background, are visible on the rule 1 through the window 5 (corresponding to the month of March, which means that the fecundity period will begin on the 26th of the month under review, i. e. on March 26th, that said fecundity period will end on the 2nd of the next month, i. e. April 2nd, and that the next menstruation will appear on the 14th day of the next month, i. e. on April 14th.

Fig. 2 of the drawings shows the other side of the apparatus.

In the guides 2 and 2' of the rule 1 moves a slide 3 provided at its extremities with a notch 4, 4'. On the top side of the guide 2 the figures 1 to 31 are inscribed, which correspond to the possible 31 days of a month, this group of figures is generally indicated by 10. On the same scale, on the top margin of the slide 3 are provided the figures 33 to 23 referring to various cycles which can be studied with this apparatus, said figures are generally indicated by 9.

In the slide 3 four windows are provided, indicated by 11, 12, 13 and 14, and referring respectively to:

11, January of a normal year having 365 days
12, February of a normal year having 365 days
13, January of a leap-year having 366 days
14, February of a leap-year having 366 days.

Thus four types of different months are given; the first is a month of 31 days followed by a month of 28 days; the second is a month of 28 days followed by a month of 31 days; the third is a month of 31 days followed by a month of 29 days; at last the fourth is a month of 29 days followed by a month of 31 days.

The use of this side of the apparatus is entirely the same as that described with respect to Fig. 1.

Example 2.—The recent menstruation of a per-

son having a menstrual cycle of 32 days has started on January 28th of a normal year having 365 days. By pushing the slide 3 in the guides 2 and 2' until the figure 32 (corresponding to the length of the cycle, provided on the slide) corresponds to the figure 28 (corresponding to the number of the day of the month, provided on the guide 2) the three figures: 10 on a yellow background, 17 on a yellow background, and 1 on a blue background are visible through the window 11, which indicates that the fecundity period will begin on the 10th of the month following the month under review, i. e., consequently, on February 10th, that it will end on the 17th of the month following the month under review, i. e. on February 17th, and that the next menstruation will appear on the 1st of the second month following the month under review, i. e. on March 1st.

Fig. 3 shows a variant of the embodiment of the object of the invention.

The rule 1 with its guides 20 and 20' carries a slide 30, provided with notches 40 and 40', on one of its sides only.

The guide 20 carries, as described in the examples of Figs. 1 and 2, the figures 1 to 31 corresponding to the possible 31 days of a month, and, opposite thereof, on the slide 30, the figures 33 to 23 corresponding to various cycles, which can be studied with the apparatus, which is the object of the present invention.

The slide 30 is provided with seven windows indicated by 50, 60, 70, 80, 90, 100, 110 corresponding respectively to:

50, March, May, August, October
60, April, June, September, November
70, July, December
80, January of a normal year having 365 days
90, February of a normal year having 365 days
100, January of a leap-year having 366 days
110, February of a leap-year having 366 days.

The manipulations to be carried out with this apparatus are in every respect entirely the same as those described with respect to Figs. 1 and 2 and need not any particular explanation.

The apparatus described with respect to Figs. 1 to 3 can be manufactured of all sorts of suitable material, like: cardboard, strong paper, metal, wood, plastic, etc. The indications like e. g. the numbers of the days of the month, the lengths of the cycle, the names of the months, the characteristic figures of the beginning and the end of the fecundity period, and the date of appearance of the menstruation to be expected, may be provided on the apparatus by any suitable means, by printing, engraving, or by printing on an individual carrier which is glued or fixed on the apparatus, without deviating from the gist of the invention by said various methods.

What we claim is:

1. An apparatus for determining the date of appearance of the next menstruation to be expected and the date of the beginning and the end of the fecundity period of a determined menstrual cycle of a woman, comprising a rule on the surface of which slides a slide provided with windows through which the indications marked on the rule and referring to the date of the beginning of the fecundity period, to the date of the end of said period, and to the date of appearance of the next menstruation to be expected, are visible, and each of the said windows

refers to a well-determined type of month, like all the months relating to one and the same window having the same number of days and followed by a month having the same number of days.

2. An apparatus as claimed in claim 1, in which the rule carries figures referring to the number of the day of a month and the slide, opposite of said figures, carries figures referring to various lengths of cycles which can be examined with the aid of this apparatus.
